Christopher P. Godziela**[57] CLAIM**

The ornamental design for a power nozzle for a vacuum cleaner, as shown and described.

DESCRIPTION

FIG. 1 is a front, left, top perspective view of a power nozzle for a vacuum cleaner showing our new design; FIG. 2 is a right side elevational view thereof; FIG. 3 is a top plan view thereof; FIG. 4 is a front elevational view thereof; FIG. 5 is a rear elevational view thereof; and, FIG. 6 is a bottom plan view thereof.

The broken-line showing of a vacuum cleaner wand in FIG. 1 is for illustrative purposes only and forms no part of the claimed design.
